(57) **CLAIM**

The ornamental design for a reusable container cover as shown and described.

DESCRIPTION

FIG. 1 is a top perspective view of a reusable container cover, showing our new design, showing the top piece and the bottom piece in an assembled configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view thereof;

FIG. 9 is an exploded top perspective view thereof, showing the top and bottom pieces in a disassembled configuration;

FIG. 10 a top perspective view of the reusable container cover as shown in FIG. 1, further shown in use with an exemplary container;

FIG. 11 is a top perspective view of the top piece of the reusable container cover, shown independent of the bottom piece to show aspects of the design not visible when combined;

FIG. 12 is a front elevation view thereof;

FIG. 13 is a rear side elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a top perspective view of the bottom piece of the reusable container cover, shown independent of the top piece to show aspects of the design not visible when combined;

FIG. 19 is a front elevation view thereof;

FIG. 20 is a rear side elevation view thereof;

FIG. 21 is a left side elevation view thereof;

FIG. 22 is a right side elevation view thereof; and,

FIG. 23 is a top plan view thereof; and,

FIG. 24 is a bottom plan view thereof.

(Continued)

The broken lines are shown for the purpose of illustrating environmental subject matter of an exemplary container and form no part of the claimed design.
